CLAIM

(57) The ornamental design for a ball marker and holder, as shown and described.

DESCRIPTION

FIG. 1 is a top, front, and left side perspective view of a ball marker and holder according to our new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a right side elevation view thereof; and,

FIG. 7 is a left side elevation view thereof.

The dot-dash broken lines represent boundaries of the claimed design and form no part of the claimed design. The dash-dot broken lines depict portions of the ball marker and holder that form no part of the claimed design.
